UNITED STATES PATENT OFFICE

WALTER T. WINCKLER, OF CHICAGO, ILLINOIS, ASSIGNOR TO VON WINKLER LABORATORIES, INCORPORATED, OF CHICAGO, ILLINOIS, A CORPORATION OF ILLINOIS

SULPHURIC ESTERS OF HALOGENATED FATTY ACIDS

No Drawing.

Application filed August 30, 1928. Serial No. 303,128.

This invention relates to an improved pharmaceutical composition of substantially the same general type as that disclosed in my copending applications bearing Serial Nos. 245,051 and 269,880, filed January 6, 1928 and April 13, 1928 respectively.

This improved pharmaceutical compound has similar medical properties and is compounded of substantially the same ingredients as those disclosed in my copending application bearing Serial No. 245,051, but the ingredients are compounded in an entirely different sequence and manner and the resulting compound has an entirely different organic structure and different properties which are better suited for the purposes herein set forth.

The main objects of my invention are to provide an improved method of making a pharmaceutical compound for avoiding decomposition and disassociation thereof in very dilute solutions; to provide a composition that is soluble in water; to provide a composition of improved stability which is capable of retaining a high value of a medicinal agent adapted for treatment of germ diseases, boils, goiter, skin diseases and infections; to provide a non-toxic germicide that will penetrate and which will not burn, stain or in any way irritate the skin.

I have found that when vegetable oils containing fatty acids are treated with a medicinal agent such as the elements of the halogen group or compounds thereof, the medicinal agent combines with the fatty acids of the oil forming saturated halogenated hydroxy fatty acids. These saturated hydroxy-fatty acids are readily converted into sulphuric ester by the treatment with concentrated sulphuric acid forming a compound having a high degree of solubility in water, which successfully resists decomposition in very dilute solutions. The resulting compound is highly disinfectant and its germicidal properties render it well suited for treatment of germ diseases, boils, goiter, skin diseases and infections.

Numerous different oils, both vegetable and animal, containing fatty acids of many different varieties, may be used in the prep-

aration of my improved pharmaceutical composition and these may be treated with medicinal agents comprising elements, or compounds containing elements, of the halogen group or other medicinal agents, but for the purpose of an illustrating and specific example of my method of producing an improved composition the following ingredients are employed:

Ricinoleic acid, an unsaturated, monobasic, fatty acid derived from castor oil beans, is mixed with water and boiled for from thirty minutes to one hour or until all albuminous matter is precipitated, coagulated and settled out. Then the ricinoleic acid is treated with a quantity of iodine substantially equal to 10% by volume of the quantity of acid. The iodine may be introduced in the form of a solution, in crystalline form or as hydriodic acid. The percentage of iodine may vary decidedly from 10% if desired, but in all events it is necessary that the quantity of iodine introduced be insufficient to saturate all of the ricinoleic acid with iodine. The iodized ricinoleic acid is then allowed to stand for five or six days before treatment with sulphuric acid.

The reaction between the ricinoleic acid and the iodine may be illustrated by the following equation:

The reaction product produced is ricinoleic acid, di-iodide, or di-iodo-mono-hydroxy-stearic acid. Although all the ricinoleic acid is not saturated with iodine because of the insufficient quantity introduced some of the ricinoleic acid takes on iodine to the extent of becoming completely saturated, and the product at the end of the iodination reaction is a saturated hydroxy-fatty acid.

The iodized ricinoleic acid is then treated with a quantity of chemically pure sulphuric acid substantially equal to 30% by volume of the product of the previous reaction at a temperature not higher than 30° C. Generally 8 hours are required to complete

this step of the process. This reaction is illustrated by the following equation:

The reaction product is sulphuric ester of di-iodo hydroxy stearic acid. This product is then separated from the by-products of the reaction and completely neutralized 10 by any suitable alkali such as sodium hydroxide producing the following sodium salt of the compound:

15 This compound is sulphuric ester of 9-10 di-iodo 7 hydroxy sodium stearate, 9-10 referring to the positions of the iodine and 7 the position of the sulphuric acid group in the fatty acid chain.

20 The sodium salt of the compound is then separated from the impurities mixed therewith by dissolving the salt in a suitable solvent such as alcohol and centrifuging the solvent off.

25 The final product may be left in a dilute state in solution in alcohol; the solution may be concentrated by driving off part of the alcohol, or all of the alcohol may be driven off by distillation leaving the sodium salt 30 of the compound in a plastic form.

Although but one specific example of my invention has been herein described, it will be understood that various changes in the details and sequence of steps of the process 35 and substitutions of ingredients may be made without departing from the spirit of this invention as defined by the following claims:

I claim:

40 1. The method of preparing a pharmaceutical compound consisting of the addition of concentrated sulphuric acid to a hydroxy fatty acid having an element of the halogen group combined therewith and forming an 45 organic sulphate of the halogenated fatty acid.

50 2. The method of preparing a pharmaceutical composition consisting of saturating unsaturated hydroxy fatty acids with a halogen element, and adding concentrated sulphuric acid to the halogenated fatty acid thereafter, and forming an alkali metal salt 55 of the resulting product.

55 3. The method of preparing a pharmaceutical compound consisting of halogenating an unsaturated hydroxy fatty acid, reacting the halogenated fatty acid with sulphuric acid thereafter, and treating the resulting product with sodium hydroxide to form a 60 sodium salt.

65 4. The method of manufacturing a germicide consisting of saturating a hydroxy fatty acid of an oil with a halogen element and adding concentrated sulphuric acid 70 thereafter, and treating the same with an

alkali metal compound to form an alkaline metal salt.

5. The method of manufacturing a pharmaceutical composition consisting of treating a vegetable oil with sufficient iodine to 70 completely iodize part of the unsaturated fatty acid thereof, treating the iodized fatty acid with sulphuric acid, and neutralizing this compound with an alkali metal compound to form a salt, dissolving the alkali 75 metal salt in alcohol, centrifuging the alcohol solution off to separate the same from impurities and concentrating the solution by the distillation of the alcohol therefrom.

Signed at Chicago this 27th day of 80 August, 1928.

WALTER T. WINCKLER.
